UNITED STATES PATENT OFFICE.

ADDISON E. AUGUSTINE, OF HACKENSACK, NEW JERSEY, ASSIGNOR TO CHESTER MACHINE CO., INC., OF NEW YORK, N. Y., A CORPORATION OF NEW YORK.

END-FLAP-FOLDING MECHANISM FOR ENVELOPE-MAKING MACHINES.

Application filed July 20, 1920. Serial No. 397,756.

To all whom it may concern:

Be it known that I, ADDISON E. AUGUSTINE, residing at Hackensack, in the county of Bergen and State of New Jersey, have invented certain new and useful Improvements in End-Flap-Folding Mechanism for Envelope-Making Machines, of which the following is a specification.

This invention relates to an envelope-making machine, and particularly to means for insuring the proper folding over of the open end flaps of envelopes during the drying operation.

In the operation of envelope-making machines, such for instance, as are described in my pending application Serial No. 360,966, filed Feb. 24, 1920, which machines are adjusted for the making of envelopes in which the open flap occurs at one side edge rather than at the bottom edge of the envelope as the envelope falls into the drying chain, it is a matter of considerable importance that the open flap be so folded as to be properly caught between the leaves of the chain as the leaves close together after the falling of the envelope. Where the open flap occurs at the bottom edge of the envelope, it is properly folded by the closing of the chain leaves but there appears to be no satisfactory way of causing the closing movement of the chain leaves to insure proper folding of open flaps occurring at the ends of the envelopes. In the making of end flap envelopes, such, for instance, as the so called "coin envelopes" and the like, it is desirable that an auxiliary mechanism be provided to fold over the end flap to a sufficient extent so that the closing leaves of the chain will engage and properly hold the flap during the passage of the envelope with the chain around the drying frame.

The essential object of the present invention, therefore, is to provide such an auxiliary mechanism, and to so design the same that it will be simple in construction and efficient in operation.

A further object is to provide for ample adjustment of the mechanism so that it may be readily made to perform its office upon envelopes of various sizes.

A further object is to provide means whereby the parts are made readily removable to facilitate the making of repairs, etc.

Other objects and aims of the invention, more or less specific than those referred to

above, will be in part obvious and in part pointed out in the course of the following description of the elements, combinations, arrangements of parts and applications of principles, constituting the invention, and the scope of protection contemplated will be indicated in the appended claims.

In the accompanying drawings which are to be taken as a part of this specification, and in which I have shown merely a preferred form of embodiment of the invention:—

Figure 1 is a vertical sectional view taken thru a portion of an envelope-making machine illustrating the present invention applied thereto in association with the drying chain thereof.

Figure 2 is a partial front elevational view of the mechanism seen in Fig. 1, portions being shown in vertical section for the better disclosure of details.

Figure 3 is a top plan view of the folding mechanism appearing in the previous views, said view diagrammatically illustrating the operation of the folding mechanism upon the envelopes, and

Figure 4 is an enlarged detail view illustrating the folding rod carrying arm.

The means herein proposed for accomplishing the objects above set forth comprises a plunger rod L which is mounted to be operated by a cam G for moving its folding rod H to properly fold the envelope-flaps.

A trap discharge device 1 of the envelope-machine is arranged to discharge the newly gummed and folded envelopes downwardly into the spaces, as 2, occurring between the fins 3 of the carrying chain. An envelope, as 4, is illustrated in Fig. 2 as having just been received from the trap 1 into one of the spaces 2.

A main drive shaft 5 is shown for driving the chain 6. This shaft has a small sprocket 7 formed, or otherwise provided thereon, about which the links of the chain move so that in rounding the shaft the fins 3, one of which is carried by each link of the chain, spread apart, as seen particularly in Fig. 1 of the drawings, to provide the spaces 2 for receiving the envelopes from the trap. Suitable means, such, for instance, as the ratchet 8, is provided preferably for rotating the shaft with a step by step movement so that the chain is made to travel in the direction as indicated by the arrows Fig. 1. 110

- The envelopes, falling from the trap 1, fall into the spaces 2 and are carried with the chain downwardly along the upper lead for a desirable distance and thence backwardly 5 along the lower lead, an appropriate roller, not illustrated, being located at the lower end of the chain for guiding the chain. Any suitable means may be provided for delivering, or ejecting, the envelopes from 10 the upper end of the lower lead of the chain. For this purpose what is familiarly known as a gripper device 9 is employed comprising one or more arms carried by a rock shaft 10, said arms having spring finger devices 11 15 at their outer ends adapted to grip and hold the envelopes while the arms swing forwardly, as indicated by the arrow 12, to deposit the envelopes in a suitable discharge mechanism.
- 20 During the travel of the envelopes from the trap 1 into the space 2, they are guided by a pair of guide plates 13 and 14. As the envelopes move downwardly along the upper lead of the chain their weight rests 25 upon the links of the chain, and suitable guide rods 15 and 16 are provided at opposite sides of the chain for preventing endwise displacement of the envelopes.
- The guide plates 13 and 14 are adjustably 30 supported so that they can be readily moved toward and away from each other for properly accommodating envelopes of different widths. For the purpose of this adjustment the guide plates are each provided with supporting rods 17 which are adjustably received within suitable apertures formed in a supporting standard 18 of the frame work of the machine. The guide rods 15 and 16 are likewise adjustably supported by means 35 of supporting rods 19 which engage the standards 18.
- 40 While the drawings, Fig. 2, illustrate only the adjustable supporting means for the guide plate and rod 14 and 16, yet it will be understood that these elements are duplicated with respect to the guide plate and rod 13 and 15.
- The plunger L is mounted to slide freely 45 within a tubular bearing member 20 which is carried by a frame piece 21 of the machine. Preferably the bearing member is formed with a threaded extension 22 which is fitted into a threaded aperture formed in the frame piece 21 so that the bearing member 50 is rendered easily removable. By this means the bearing member and the parts carried thereby may be readily removed whenever occasion requires.
- 55 The plunger is preferably made of two sizes so as to provide a shoulder 23 thereon within the bearing member so that a compression spring 24, arranged within the bearing member and engaging between the shoulder 23 and an opposing shoulder 25 formed upon the bearing member, may be

effective in normally retaining the plunger in its outer position. An anti-friction roller 26 is provided at the outer end of the plunger for engaging against the face of the cam G and the contour of the cam is such that 70 it provides a plurality of extending portions 27 for successively engaging the roller 26 to force the plunger inwardly during the rotation of the cam.

The folding rod H is arranged at the 75 inner end of the plunger rod. It is connected with the folding rod carrying arm 28 which is in turn attached to the inner end of the plunger rod. Any suitable means may be employed for adjustably connecting 80 the folding rod with its carrying arm but preferably the carrying arm is simply provided with an aperture 29 thru which the folding rod extends. Two clamp nuts, as 30 and 31, are threaded upon the folding 85 rod for clamping against opposite sides of the carrying arm to hold the folding rod in any position of longitudinal adjustment to which it may be moved with respect to the carrying arm. The extreme end portion, as 90 32, of the folding arm may in this way be made to occupy a position at any desired and appropriate distance beyond the face of the carrying arm.

The carrying arm may be connected with 95 the plunger rod L in any appropriate manner, but preferably is connected by being formed with a slot 33 longitudinally thereof thru which a reduced extension 34 of the plunger rod projects. A shoulder portion 100 35, provided upon the plunger rod by the formation of the extension 34, furnishes a proper surface against which the carrying arm may be clamped by means of a clamp device, as for instance the nut 36 threaded upon the extension 34, to hold the carrying arm in any position to which it is moved with respect to the plunger rod. By these devices the folding rod H is made readily 105 adjustable toward and away from the axial line of the plunger rod and to any selected radial position relative to the plunger rod.

110 By the simple means of adjustment thus afforded, the end portion 32 of the folding rod is made universally adjustable so that 115 it can be made to stand and function in any position desired by the operator for properly performing the act of folding down the envelope flaps, as 37.

120 It may be noted also that by the removal of the nut 36 the folding rod and its carrying arm may be entirely detached from the plunger rod. Either a folding rod or carrying arm, or both, of a different size, 125 may be then substituted, or the removed parts may be repaired and returned, as occasion may demand.

The provision for universal adjustment is particularly essential since obviously the precise position of the folding rod must be 130

altered with practically every change of the machine for making different sized envelopes.

The guide plate 14 is suitably cut-away 5 to provide for ample adjustment of the folding rod while the guide plate 13 serves to positively prevent endwise movement of the envelope during the operation of the folding rod.

10 The cam G is mounted directly upon the drive shaft 5 to revolve therewith. The raised portions 27 of the cam are properly spaced apart so that one occurs for operating the plunger coincident with the passage 15 of each of the succeeding fins 3 of the chain. Since both the cam and the sprocket 7 are rigid upon the shaft 5, it is apparent that the rotation of the sprocket for forming the envelope receiving spaces 2, and the rotation 20 of the cam for operating the plunger, may be maintained correctly timed so that the movements of the folding rod will occur coincident with the formation of the envelope receiving spaces.

25 The cam G may, if desired, be connected with the shaft 5 so as to be rotatably adjustable thereon to the end that the timing of the operation may be altered to suit varying requirements. For this purpose the cam 30 may be loose upon the shaft and may be provided with a sleeve 38 thru which extends a set screw 39 by which to hold the cam in any position of adjustment to which it may be moved.

35 One or more bearings, as 40, may be provided for rotatably supporting the shaft 5.

To hold the plunger rod L against rotation within the bearing 20, said rod is herein indicated as being provided with a small 40 radially projecting pin 41 which slides within a longitudinally extending groove 42 inferiorly of the bearing.

The flap folding mechanism thus described is at once simple in construction and positive and efficient in its operation. Its adjustments may be readily and easily made so that it will properly fold the end flaps of envelopes of different sizes, and its construction and manner of attachment are 50 such that it may be easily removed from the machine whenever desired.

The timing of the folding operation may be altered to suit requirements by simply rotating the cam G more or less about the shaft 5. Wherever in the claims the timing of the folding operation is referred to, such reference is meant merely to define a structure in which the folding over of the envelope flap is accomplished in proper relation to the movements of the envelope carrier so that the flap is folded in time to be correctly held by the carrier.

As many changes could be made in this construction without departing from the 65 scope of the invention as defined in the fol-

lowing claims, it is intended that all matter contained in the above description, or shown in the accompanying drawings, shall be interpreted as illustrative only and not in a limiting sense.

Having thus described my invention, what I claim as new and desire to secure by Letters Patent is:—

1. In an envelope-making machine, the combination with a movable carrier for receiving the newly gummed envelopes, means to move said carrier, and means for delivering envelopes into said carrier, of means movable to fold the end flaps of the envelopes as the envelopes are delivered into said carrier, and means positively connected with the carrier operating means for effecting operation of the flap folding means coincident with the movements of the carrier. 75

2. In an envelope-making machine, the combination with a movable carrier for receiving the newly gummed envelopes, means to move said carrier, and means for delivering envelopes into said carrier, of flap folding means for folding the end flaps of the envelopes as the envelopes are delivered into said carrier, said flap folding means comprising a plunger rod, an element urging the plunger rod out of flap folding position, and a cam positively connected with said carrier 90 operating means for effecting movement of said plunger rod into folding position coincident with the movements of the carrier. 95

3. In an envelope-making machine, the combination with a movable carrier for receiving the newly gummed envelopes, means to move said carrier, and means for delivering the envelopes into said carrier, of flap folding means for folding the end flaps of the envelopes as the envelopes are delivered 100 into said carrier, said flap folding means comprising a plunger rod, a flap folding rod, a carrying arm upon which said folding rod is mounted, means adjustably connecting said carrying arm with said plunger 105 rod providing adjustment of the folding rod either toward or away from the plunger rod, and means positively connected with the carrier operating means for effecting 110 operation of the flap folding means coincident with the movements of the carrier. 115

4. In an envelope making machine, the combination with a movable carrier for receiving the newly gummed envelopes, means to move said carrier, and means for delivering envelopes into said carrier, of flap folding means for folding the end flaps of the envelopes as the envelopes are delivered into said carrier, said flap folding means comprising a plunger rod, a folding rod, one end 120 of which serves for engaging and folding the envelope flap, means whereby said mentioned end of the folding rod is universally adjustable relative to the plunger rod, and means positively connected with the carrier 125 130

operating means for effecting operation of the flap folding means coincident with the movements of the carrier.

5. In an envelope-making machine, the combination with a movable carrier for receiving the newly gummed envelopes, means to move said carrier, and means for delivering the envelopes into said carrier, of flap folding means for folding the end flaps of the envelopes as the envelopes are delivered into said carrier, said flap folding means comprising a plunger rod, a part carried at one end of said plunger rod for engaging the envelope, a cam positively connected with said carrier operating means engaging the opposite end of the plunger for operating the plunger coincident with the operations of the carrier, a support, and a bearing for said plunger detachably connected with said support for the purpose set forth.

6. In an envelope-making machine, the combination with a movable carrier for receiving the newly gummed envelopes, means to move said carrier, and means for delivering the envelopes into said carrier, of flap folding means for folding the end flaps of the envelopes as the envelopes are delivered into said carrier, said flap folding means comprising a plunger rod, a cam positively connected with said carrier operating means engaging one end of the plunger rod for operating the plunger rod coincident with the operations of the carrier, an envelope-flap engaging part connected with the plunger rod at the opposite end thereof, and means connecting said envelope-flap engaging part with said plunger rod of a character rendering the envelope-flap engaging part both universally adjustable with respect to, and bodily detachable therefrom.

7. In an envelope making machine, the combination with a movable carrier for receiving the newly gummed envelopes, means to move said carrier, and means for delivering envelopes into said carrier, of flap folding means for folding the end flaps of the envelopes as the envelopes are delivered into said carrier, said flap folding means comprising a plunger rod, a cam positively connected with said carrier operating means engaging one end of the plunger rod for operating the plunger rod coincident with the operations of the carrier, an arm arranged at the opposite end of the plunger rod projecting laterally therefrom, means connecting said arm with said plunger rod affording adjustment of said arm to project a greater or less distance radially from said plunger, and a flap folding rod carried at the outer end of said arm.

8. In an envelope-making machine, the combination with a movable carrier for receiving the newly gummed envelopes,

means to move said carrier, and means for delivering envelopes into said carrier, of flap folding means for folding the end flaps of the envelopes as the envelopes are delivered into said carrier, said flap folding means comprising a plunger rod, a cam positively connected with said carrier operating means engaging one end of the plunger rod for operating the plunger rod coincident with the operations of the carrier, an arm arranged at the opposite end of the plunger rod projecting laterally therefrom, said arm having an opening therethru at its outer end, a flap folding rod longitudinally adjustable within said opening, said rod being substantially parallel with said plunger, and means to retain said rod in any selected position of longitudinal adjustment within said opening.

9. In an envelope-making machine, the combination with a movable carrier for receiving the newly gummed envelopes, means to move said carrier, and means for delivering envelopes into said carrier, of flap folding means for folding the end flaps of the envelopes as the envelopes are delivered into said carrier, said flap folding means comprising a plunger rod, a cam positively connected with said carrier operating means engaging one end of the plunger rod for operating the plunger rod coincident with the operations of the carrier, an arm arranged at the opposite end of the plunger rod projecting laterally therefrom, means connecting said arm with the plunger rod of a character rendering the arm capable of movement to extend in any selected direction radially of the plunger rod, said connecting means also being of a character to enable adjustment of said arm to project a greater or less distance radially from the plunger rod, means to hold said arm in any position to which it may be adjusted, and flap folding means carried at the outer end of said arm.

10. In an envelope-making machine, the combination with a movable carrier for receiving the newly gummed envelopes, means to move said carrier, and means for delivering envelopes into said carrier, of flap folding means for folding the end flaps of the envelopes as the envelopes are delivered into said carrier, said flap folding means comprising a plunger rod, a cam positively connected with said carrier operating means engaging one end of the plunger rod for operating the plunger rod coincident with the operations of the carrier, an arm arranged at the opposite end of the plunger rod projecting laterally therefrom, means connecting said arm with the plunger rod of a character rendering the arm capable of movement to extend in any selected direction radially of the plunger rod, said connecting means also

- being of a character to enable adjustment of said arm to project a greater or less distance radially from the plunger rod, means to hold said arm in any position to which it may be adjusted, flap folding means carried by the outer end of said arm, and means whereby said flap folding means is rendered adjustable in a direction longitudinally of said plunger rod.
- 10 11. In an envelope-making machine, the combination with means for gumming and forming the envelope but leaving one flap of the envelope in a partially folded condition, and receiving means for the newly formed envelopes, of means operable to further fold said mentioned flap prior to receipt of the envelope by said receiving means.

12. In an envelope-making machine, the combination with means for gumming and forming the envelope but leaving one flap of the envelope in a relatively open condition, receiving means for the newly formed envelopes, and means whereby the newly formed envelopes will be delivered from said forming means to said receiving means, of means arranged to engage the envelope as it is received by said receiving means and to partially fold said mentioned flap.

In testimony whereof I affix my signature in the presence of two witnesses.

ADDISON E. AUGUSTINE.
